UNITED STATES PATENT OFFICE.

WILLIAM N. HENSLEY, OF COLUMBUS, NEBRASKA, ASSIGNOR OF ONE-HALF TO THOMAS F. WILSON, OF COLUMBUS, NEBRASKA.

EMERGENCY-COUPING.

No. 800,299.

Specification of Letters Patent.

Patented Sept. 26, 1905.

Application filed September 29, 1904. Serial No. 226,526.

To all whom it may concern:

Be it known that I, WILLIAM N. HENSLEY, of Columbus, in the county of Platte, and in the State of Nebraska, have invented a certain new and useful Improvement in Emergency-Couplings; and I do hereby declare that the following is a full, clear, and exact description thereof, reference being had to the accompanying drawings, in which—

10 Figure 1 is a side elevation showing an embodiment of my device applied in coupling a disabled car-coupling to a car-coupling which is intact. Figs. 2, 3, and 4 are respectively top, side, and bottom elevations of my emergency-coupling by itself.

15 The object of my invention has been to provide an emergency-coupling by which a car having a broken coupling can be readily and efficiently coupled to a car having a Master Car-Builders' coupling that is intact, so that a car having a disabled coupling can be transported as readily and safely as if its coupling were not disabled; and to such ends my invention consists in the emergency-coupling hereinafter specified and claimed.

20 Prior to my invention when a car-coupler was destroyed or injured it has been customary to attach a "bull-chain" to a transom of the car-truck and then to secure such chain, as by a pin, to the coupling of another car. In order that the bull-chain might stand the strains to which it is subjected in pulling the car, such chain has of necessity been made so heavy that the slack could not be taken out 25 of it by the pull of the hands, and the result has been that the cars were not closely coupled together, and serious bumping occurred during transportation. Moreover, the attempt to fasten the bull-chain by a pin to the coupling of the adjacent car has been unsatisfactory. The coupling which is the subject of my invention effectively overcomes these objections.

25 My coupling consists of a body A, having at one end a knuckle B, which is adapted to be received in an intact Master Car-Builders' coupling, the knuckle B being provided with a lip b, which is adapted to rest upon the upper surface of the knuckle with which it is coupled, so as to properly support the body A and prevent its falling. The opposite end of the body A is provided with an arm C, that is adapted to be received in the draw-head of

the injured coupling or in the space provided for the draw-head in the bumper of the car. 55 A bumper D is formed on the body A at the base of the arm C, such bumper being adapted to bear against the draw-head or bumper of the disabled car. Between the knuckle B and the bumper D an opening E is formed in 60 the body A, and a forked catch F is formed on such body. The catch F is formed with an upwardly-directed plate-like portion f, that is inclined toward the knuckle B and that is supported by strut-like portions f', 65 formed integral with the body A and with the plate-like portion f of the catch. The fork of the catch F forms a slot f² of such width as to receive a link of the bull-chain when in vertical position, but to prevent the passage 70 therethrough of such a link when in a horizontal position. Beneath the opening E and somewhat to the rear of its forward wall a windlass H is mounted in lugs formed on the car-body, the said windlass consisting simply 75 of a cylindrical shaft h, having a head h', in which are formed holes h², through which a bar may be passed to turn the windlass. A ratchet I is formed on or secured to the shaft h, and a pawl K is pivoted to the side of the 80 coupler-body A in position to engage the ratchet-wheel. The pawl may conveniently be made in the form of a ring k, having a pawl-tooth k' formed on its inner edge and having a shank k², by which it can be pivoted. The ring tends to prevent the pawl 85 from being shaken out of operative position.

85 In the operation of my emergency-coupler the knuckle B is engaged in the knuckle of the coupler which is intact. The bull-chain 90 is secured to a transom of the truck of the disabled car, as by passing such chain around said transom and hooking the end of the chain to the body thereof. A small chain L is secured on the drum of the windlass formed 95 by the shaft h and is attached to the bull-chain in any desired manner. The windlass is then turned to draw the bull-chain taut and, if necessary, to draw the cars together, the arm C being directed into the disabled 100 draw-head or into the space which was occupied thereby. The bull-chain is passed up through the opening E, and when it has been drawn sufficiently taut one of its vertical links is passed into the slot f², thus securely 105 coupling the cars together.

It will be obvious that I have provided a simple and efficient coupler by which a disabled car can be coupled to a car having a coupler that is intact and that the cars can be held as closely together as desired and objectionable bumping prevented.

I do not desire to be limited beyond the letter of my claims or the requirements of the prior art.

10 It is obvious that various changes can be made in the above-illustrated construction.

Having thus described my invention, what I claim is—

15 1. In an emergency-coupling, the combination of a body having a knuckle adapted to be engaged by a Master Car-Builders' coupling, and having a shank adapted to enter a socket on an opposite car, and means on said body for engaging a chain.

20 2. In an emergency-coupling, the combination of a body having a knuckle adapted to be engaged by a Master Car-Builders' coupling, and having a shank adapted to enter a socket on an opposite car, and means on said body for engaging a chain, said body having a lip or projection adapted to bear upon the upper surface of the knuckle of said coupling.

25 3. In an emergency-coupling, the combination of a body having a knuckle adapted to engage a Master Car-Builders' coupling, said knuckle having a lip or projection adapted to bear upon the upper surface of the knuckle of the said coupling.

30 4. In an emergency-coupling, the combination of a body having a knuckle adapted to engage a knuckle of a Master Car-Builders' coupling, and means on said body for drawing a chain taut.

35 5. In an emergency-coupling, the combination of a body having means for engaging a coupler that is intact, and a windlass on said body for drawing a coupling-chain taut.

40 6. In an emergency-coupling, the combination of a body having means for engaging a coupling that is intact, a windlass mounted on said body for drawing a coupling-chain taut, and a fork extending upwardly and in the direction of said first-mentioned means, said fork being adapted to engage a vertical link in the said coupling-chain.

45 7. In an emergency-coupling, the combination of a body having a member corresponding to the coupling-engaging member of an intact coupling, said body having at its opposite end an arm or extension adapted to enter the draw-head of an injured coupling, said body having a vertical, central opening, a windlass journaled horizontally across the lower entrance to said opening, and a fork extending above the upper entrance to said opening.

50 8. In an emergency-coupling, the combination of a body having a member corresponding to the coupling-engaging member of an intact coupling, said body having at its

opposite end an arm or extension adapted to enter the draw-head of an injured coupling, said body having a vertical, central opening, a windlass journaled horizontally across the lower entrance to said opening, and a fork extending above the upper entrance to said opening, said coupling being provided with a bumper at the base of said arm.

55 9. In an emergency-coupling, the combination of a body having a member corresponding to the coupling-engaging member of an intact coupling, said body having at its opposite end an arm or extension adapted to enter the draw-head of an injured coupling, said body having a vertical, central opening, a windlass journaled horizontally across the lower entrance to said opening, and a fork extending above the upper entrance to said opening, said windlass being provided with a pawl and ratchet to prevent rotation.

60 10. In an emergency-coupling, the combination of a body having a member corresponding to the coupling-engaging member of an intact coupling, said body having at its opposite end an arm or extension adapted to enter the draw-head of an injured coupling, said body having a vertical, central opening, a windlass journaled horizontally across the lower entrance to said opening, and a fork extending above the upper entrance to said opening, said windlass being provided with a pawl and ratchet to prevent rotation, said ratchet being provided with a loop or ring that embraces the ratchet-wheel.

65 11. In an emergency-coupling, the combination of a body having a member corresponding to the coupling-engaging member of an intact coupling, said body having at its opposite end an arm or extension adapted to enter the draw-head of an injured coupling, said body having a vertical, central opening, a windlass journaled horizontally across the lower entrance to said opening, and a fork extending above the upper entrance to said opening, said windlass being provided with a lighter chain for engagement with said coupling-chain to draw the latter taut.

70 12. In an emergency-coupling, the combination with a knuckle adapted to interlock with a Master Car-Builders' coupling, of a connection secured to said knuckle and adapted to be secured to the frame of an adjoining car, and means for taking up the slack in said connection.

75 13. In an emergency-coupling, the combination with a knuckle adapted to interlock with a Master Car-Builders' coupling, of a connection extending from said knuckle and adapted to be secured to the frame of an adjoining car, and means for adjustably securing said connection to said knuckle.

80 14. In an emergency-coupling, the combination with a knuckle adapted to interlock with a Master Car-Builders' coupling, of a chain extending from said knuckle and

adapted to be secured to the frame of an adjoining car, and means for adjustably securing said chain to said knuckle.

15. In an emergency-coupling, the combination with a knuckle adapted to interlock with a Master Car-Builders' coupling, of a chain extending from said knuckle and adapted to be secured to the frame of an adjoining car, said knuckle having a slot therein of a width to receive and hold a link of said chain.

16. In an emergency-coupling, the combination with a body portion, of means on said

body portion for securing the same to a car-coupling, a connection extending from said body portion and adapted to be secured to the frame of an adjoining car, and means for adjustably securing said connection to said body portion.

In testimony that I claim the foregoing I have hereunto set my hand.

WILLIAM N. HENSLEY.
